UNITED STATES PATENT OFFICE

JAMES BLACKLOCK HENDERSON, OF BLACKHEATH, ENGLAND

GOLF CLUB AND HOME PRACTICING DEVICE

Application filed February 17, 1927, Serial No. 168,973, and in Great Britain October 18, 1926.

My invention relates to golf clubs and home practicing devices and has for its object the provision of means whereby the beginner and expert alike may detect errors in the orientation of the driving face of the club in the position of impact with the ball and may also know which of two angular adjustments of the club face must be made to correct the error. It is notorious that in golf the only practice which is effective is that on the links actually playing a ball and that even then it is difficult for the expert, and practically impossible for the beginner, to determine what faults he is committing if he is "off his game". To swing a club indoors for practice is practically useless and is in fact often the cause of acquiring habits which lead to mistakes in actual play. My invention for the first time gives the golfer definite information as to the exact position of the club face at the moment of impact with a ball, real or imaginary, so that mistakes can be instantly detected and bad habits eradicated either in actual play out of doors or in practice at home. Home practice without a ball can thus be made a direct means to improving one's game and need no longer be regarded as a source of bad habits.

The first essential for an effective stroke at golf is that the normal to the driving face of the club at the moment of impact with the ball shall lie along the required trajectory of the ball. Heretofore no one seems to have devised a means of testing whether this first essential is satisfied or not during practice without a ball, but these means are now provided by my invention.

The means provided are best described by reference to the accompanying drawings, in which

Fig. 1 illustrates one adaptation of my invention, in which a single reflector is used.

Fig. 2 shows another adaptation employing two reflectors and two sources of light.

Fig. 3 is the preferred form of the invention, employing two reflectors and one source of light.

Figs. 4a and 4b show respectively a sectional elevation and plan of one arrangement

for fixing the reflectors to the head of a wooden club.

Figs. 5a and 5b show an attachment for riveting to iron clubs.

Figs. 6a and 6b are sectional elevation and plan of a universally adjustable attachment for use with drivers and the like.

Figs. 7a and 7b show sectional elevation and part plan of a universally adjustable attachment for use with iron clubs.

Figs. 8a and 8b show elevation and plan of an alternative adjustable attachment for wooden clubs.

Figs. 9 and 10 show club heads fitted with detachable weights to compensate the weight of the reflectors when in use.

Fig. 11 shows an arrangement for obtaining a line of light when practicing with a ball out of doors.

Referring to Fig. 1 the club head 1 has a driving face 2, the centre of which is O. Three axes, OX, OY and OZ are drawn through O, OY being vertical, OX horizontal in the plane of the club face and OZ horizontal and at right angles to both OX and OY. ON is the normal to the driving face 2. At the moment of impact with the ball, real or supposed, it is required that ON shall lie along the required trajectory of the ball.

Suppose that a beam of light were projected back along the required trajectory towards O and that a reflector 3 were fixed to the club face 2 and so oriented that when the club head is in the correct position of address the beam NO is reflected up to the player's eye at E. If the player now swings his club he will see a flash of light from the mirror as the club head passes through the position of address, provided that the club face is at that moment in the required plane at right angles to the trajectory ON. If he sees no flash at all, or if he sees it too soon or too late he knows that the club head has been wrongly oriented at the moment of supposed impact and that if he had been playing a real ball, the ball would not have been struck along the required path ON.

With this mechanism, however, the player could not tell whether the club face had been wrongly oriented about OX or OY. Incorrect orient-

60

70

75

80

100

tation about OX is the error known as "hands lagging" or "hands leading", causing the flash to occur late or early respectively. An error in orientation about the axis OY, known as "nose of the club in (or out)" will similarly displace the position of the flash, or if serious may show no flash at all. Rotation of the club head about OZ caused by raising or lowering the hands does not affect the trajectory but will prevent the player from seeing any flash. With the mechanism shown in Fig. 1 it is therefore obvious that a player would be aware that he is making mistakes, but he could not detect which mistake or mistakes he is making. It is therefore necessary to provide separate means to detect separate errors, particularly errors in orientation about the axes OX and OY. One such arrangement is shown in Fig. 2.

On the top of the club head 1 a metal plate 4 is fixed by wood screws 5. The plate 4 has two metallic reflectors 6 and 7 soldered or otherwise rigidly attached to it. These reflectors may conveniently be of rustless steel highly polished. In the position of address, which I shall at first assume to be central to the player, 6 is horizontal and 7 is parallel to OZ. I place a line of light lamp 8 at some distance, say 6 feet, from the mirror 6 so that a portion of its image in 6 is seen by the player in the position of address, and I place a second line of light lamp 9 equidistant from the mirror 7 in the direction OX, the reflector 7 being inclined so that the player also sees a portion of the image of 9 in the mirror 7 in the position of address. If the player now swings his club as in a drive he ought to see two simultaneous flashes, one in each mirror, at the moment when the club face meets the supposed ball. If the club face is wrongly adjusted by one degree about OX the flash from mirror 6 will occur about one inch too soon or too late, "hands leading" making it occur early. Similarly if the club face is incorrectly oriented about the axis OY by one degree, the flash in mirror 7 will occur about one inch too soon or too late. Rotation about OX, however, will also affect the position of the flash from mirror 7, but rotation about OY will not affect the flash from mirror 6.

Fig. 3 shows a better arrangement in which I employ only one lamp and which I prefer because it makes the two flashes more independent, one flash denoting approximately rotation around OX and the other that about OY. The plate 4 in this case is shown wedge shaped and carries the plain reflector 6 and a double reflector 10 consisting of two metallic reflectors 10a and 10b substantially at right angles to each other, the line of intersection of their faces being parallel to the reflector 6 and also to the driving face 2. A line of light lamp 11, placed from $1\frac{1}{2}$ to 6 feet away, the distance altering the sensitiveness, is so placed

that in the position of address the player sees a portion of its image in both reflectors 6 and 10. The wedge 4 is introduced to give the lamp 11 an elevation of about 45° in the position of address and so make the sensitiveness of both mirrors the same, though this is not essential. The line of light from the player's eye to the club head is generally inclined more steeply than 45° and if the mirrors were horizontal the necessary higher elevation of the lamp 11 would diminish the sensitiveness of the mirror 10. It is possible to increase this sensitiveness by other means, as will be referred to later, so that the 45° angle is not a necessary elevation for equal sensitiveness. The mirrors 6 and 10 respectively give accurately the adjustments about two axes OX' and OY' turned around OZ through the angle of the wedge 4.

The line of light lamp eliminates the necessity for adjustment about OZ to make the flash visible, but instead of a line of light lamp as source I may alternatively use an ordinary lamp and make the surface of the mirror 6 and one of the reflectors 10a or 10b or both cylindrical, the axis of the cylinder being parallel to OZ in the case of the mirror 6 and parallel to the 45° end edge in 10a or 10b. The cylindrical reflector may be either convex or concave. Each form would equally eliminate the adjustment about OZ but the appearance of the flash would differ in the two cases. If the mirror is convex, the flash, instead of being the full size of the mirror, would be reduced to a line of light whose length is equal to the width of the mirror.

I may also vary the sensitiveness of the device by making one or more of the reflectors concave or convex in two planes, which displaces the image of the light in the mirror further from or nearer to the mirror and so alters the sensitiveness as though the light itself had been moved further away or brought nearer to the club so as to increase or decrease the lateral displacement of the flash for a given displacement of the club head around the axes OX or OY. The reflector may be either spherical or astigmatic.

Figures 4 to 8 show various methods of attaching the device to the club head.

Figs. 4a and 4b show sectional elevation and plan of an arrangement of mirrors similar to Fig. 3 for attachment to wooden clubs. The plate 4 carrying the reflectors 6 and 10 is permanently fixed to the club head by screws, a flat being previously cut or filed on the club head, at the correct angle, to receive it.

Figs. 5a and 5b show a method of attaching the reflectors by rivets to the blade of an iron club.

Figs. 6a and 6b show sectional elevation and plan of an adjustable attachment for the mirrors for use with wooden clubs. The plate 4 carrying the reflectors 6 and 10 has a spherical seat 15 engaging with a circular washer 16

and the single fixing screw 17 has a concentric spherical head, so that by slightly slackening the screw the plate 4 can be angled in any of the three planes about OX, OY, OZ 5 and adjusted to reflect the light into the player's eye in the position of address and then fixed in position by tightening the screw. It will be understood that angling the plate 4 about the reflecting edge of the mirror 10, 10 i. e. about OX' in Fig. 3 has no effect on the flash from 10 but only affects the flash from 6, while angling the plate about the axis OY' (Fig. 3) only affects the flash from 10 and not that from 6. 15 Figs. 7a and 7b are sectional elevation and part plan of a similar type of fixing to Fig. 6 but adapted for attachment to iron clubs. The drawings are self-explanatory.

Figs. 8a and 8b show an arrangement similar to Fig. 4 but attached to the club by three screws 18 with spring washers 19 below the plate so as to be adjustable about any horizontal axis.

The additional weight of the reflectors 25 naturally affects the swing of the club and in wooden clubs for practice the additional weight can be compensated by removing some of the lead from the club head, as the amount of lead usually employed in such 30 clubs exceeds in weight the weight of the device. In iron clubs I may reduce the weight of the reflectors and their attachments to a minimum by using duralumin or other light alloy and I may construct club heads specially 35 to take the reflectors with removable weights equivalent to the weight of the reflector, these detachable weights being removed when the device is attached.

Fig. 9 shows a section of a wooden club 40 with a detachable weight. The weight 20 is set in a recess 21 in the club head and is fixed by a screw 22.

Fig. 10 shows a section of an iron club head also fitted with a detachable weight 24 45 fitted into a recess 25 in the back of the blade and fixed by a screw 26.

The invention is applicable to practice out of doors with a ball as well as at home without one. There is of course no objection to 50 practicing out of doors without a ball, but by using a ball interesting comparisons can be made between the practice swing, watching the flash, and the resultant travel of the ball. For this purpose I employ, in place of

55 the line of light lamp, a device shown in Fig. 11. It consists of a slotted screen, which may consist of a broad board 31 with a rotatable dial 32 in its centre having a slot 33 across it, the slot being $\frac{1}{2}''$ to $1''$ wide, arranged on any suitable stand so that the screen is inclined to the ground at about 45° . The screen should be painted dull black and should be situated so that the slot is illuminated by the sky behind or by a lamp. By 60 teeing a ball in the plane containing the slot

and the player's eye and, say, two or three feet away from it the ball may be played and the flashes from the reflectors simultaneously observed. In this way a player may learn the position of the flashes for a good stroke with 70 his particular stance and particular method of holding the club and of swinging it, and will then be able to practise that particular swing at home without a ball or in actual play without the reflectors. 75

I have assumed so far that in the position of address the ball is centrally placed relatively to the player, a position frequently used with lofted iron or wooden clubs. The position of address varies considerably with 80 the club used and with the same club used by different players, but in general the position of the ball moves to the left of the centre as the loft on the club decreases and for a driver may be opposite or even beyond the left foot 85 position. In order to deal adequately with all positions of address I have devised the universal adjustment shown in Figs. 6a, 6b and Figs. 7a, 7b. I choose the position of the ball and of the lamp in relation to the stance 90 so that the lamp, the centre of the player's head and the reflectors are all in the same plane when the club head is in the position of striking the ball, this plane being either vertical or inclined and no great accuracy being required. 95

First consider this plane to be vertical. If the line of light is vertical it remains vertical and if inclined at 45° to the horizontal it remains so but is pointed at the 100 player's head so that it will not be square to the trajectory unless the ball is opposite the centre of the player's body. The reflectors must then be adjusted on the club head by means of the universal attachment so that the reflecting edge of the mirrors 10 lies in this 105 same vertical plane when in the position of address, and the reflectors are angled about this edge and in the vertical plane until the player sees the reflection of the line of light 110 in both mirrors at the moment of impact. Some players turn their club around OZ between address and swing so much that the length of the line of light may be insufficient 115 to cope with it, in which case an adjustment of the lamp parallel with the line of light or towards the player may be necessary to make the flashes visible. 120

Next consider the case in which in every 125 stance the relative positions of the ball, lamp and player are so arranged that the line of light, the two reflectors and the centre of the player's head all lie in a plane which is at right angles to the plane of the trajectory though possibly inclined to the vertical. (In the case first considered the plane is vertical but is inclined to the plane of the trajectory unless the player is standing exactly opposite the ball.) This method has the advantage that less adjustment of the reflectors is 130

required with variation of the stance. The reflecting edge of the double-reflecting mirror 10 is kept always parallel with the club face and I place the line of light in the inclined plane passing through the double reflecting edge and the centre of the player's head, the line of light being either parallel with the trajectory plane or pointing towards the player. This arrangement obviates the necessity for adjusting the reflectors around a vertical axis and the arrangement of Figs. 8a and 8b would suffice for all stances.

I find by practicing with a wooden driver fitted with an arrangement of mirrors similar to Fig. 3 that the position of the flash is very sensitive to changes in the swing such as tightening the grip, "slow back", and the position in which the wrist action is brought into play. The flash from mirror 10 ought to occur at or very near the position of impact but the flash from reflector 6 may occur later, indicating that the face of the club has had extra loft given to it by the player's wrist action, or earlier, indicating that the loft has been decreased, in which case the drive would be low. In fact this advance or retard of the flash from mirror 6 may be deliberately practised with a view to acquiring the knack of driving high, in the one case, as when driving with the wind behind, or driving low against the wind. It is probable that every player will adjust the mirrors to suit his average swing so that the flashes occur normally at the position of impact, and he will then be able to detect and correct the abnormal and to experiment with changes in his swing.

In order to adjust the line of light in Fig. 11 to suit different positions of address so that the line will always point at the player, I fit the slot 33 in the circular dial 32 so that by rotating the dial the slot may be turned in the plane of the board at will.

The club face is in contact with the ball through a small arc and during this time of contact the club head may turn appreciably about OX or OY. Rotation around OY will reflect the trajectory laterally and around OX will alter its elevation. I may in some cases fit an additional reflector or reflectors to detect these rotations, say one similar to 10 arranged to flash with correct orientation of the club about 4" or 6" after passing through the position of address. This would detect errors in the "follow through" but is a refinement.

It has been pointed out that the sensitivity of the detector varies with the distance of the club head from the source of light. Beginners, and even experts, will find it an advantage to commence practice with this device with the ball close to the lamp, say 18" away from it, and then gradually to increase the distance between the ball and the lamp as their skill increases.

The lamp itself may be a line of light lamp of the long cylindrical type with a long filament, or it may be an ordinary electric light bulb, oil lamp, or gas jet fitted with a suitable shade. I have used with complete satisfaction an extemporized lamp consisting of a small electric table lamp, the lamp holder of which can be tilted relatively to the standard and clamped at various angles. For the ordinary shade I have substituted a long cylindrical shade of sheet tin closed at the ends, 12" long and 4" diameter. A slot about $\frac{3}{4}$ " wide is cut the whole length of the tin parallel with its axis and a piece of tissue paper pasted over the slot. A 60 watt lamp is placed in the lamp holder through a hole in one end of the shade and the lampholder and shade are then angled on the standard so that the slot is on the underside and inclined approximately at 45° to the floor. The standard may stand on the floor or may of course be raised higher by placing it on a box or table or other convenient support. When the light is switched on the inside of the tin acts as an efficient reflector to illuminate the slot and the paper diffuses the light, giving the same effect as a long cylindrical lamp of opalescent glass.

In practice without a ball a mark should be used to represent the ball. This may be a spot in the pattern of the carpet or floor covering or a white disc may be pinned to the floor or marked with paint or chalk. The necessity for watching the flashes with this device serves the useful purpose of teaching the player to keep his eye on the ball.

It will, however, be evident that if at the moment of impact the position of the player's head differs from that which it occupied when addressing the ball, the position of the flash will be affected. This fault of moving the head, however, is the most easily detected fault in golf as the player has only to look in a mirror either at his own image or the image of anything in the room during a swing to detect the motion of his head by the motion of the image relatively to the edge of the mirror. Except for motion of the head my invention denotes accurately the position of the club head at the instant when the flashes occur.

In using the device illustrated in Fig. 3 I find that a distance of from 18" to 3 feet between the club head and the lamp gives satisfactory results, producing a displacement of the flashes of about $\frac{1}{4}$ " to $\frac{1}{2}$ " per degree tilt of the club head. The further away the lamp is placed the greater is the displacement of the flash, but even at 1 foot distance the average player may find difficulty in repeating the same swing time after time.

Although I have described the optical devices to detect the orientation of the club as metallic reflectors I may employ any other

well known optical equivalent, such as glass mirrors, or glass prisms used either as reflectors or refractors, or lenses either alone or in conjunction with reflectors.

Whereas I have described my invention so far, as means for indicating to the user of the golf club the orientation of the face of the golf club at or near the position of impact, it is obvious that the same means may be used to indicate the orientation of the face of the golf club to someone other than the user of the club say to a teacher who is instructing the user in the art of golf and the same reflectors on the golf club may be used to indicate the orientation to both the user and the instructor by suitably placing a line of light for each of them and taking up certain positions relatively thereto. Thus if the instructor stands facing the user of the club and beyond the ball a line of light suitably placed behind the user and visible between his legs or placed immediately in front of him and between him and the ball would give flashes in the reflectors on the club head which would be seen by the instructor and would indicate to him the orientation of the club face at the time of impact.

I claim:—

1. The combination with a golf club, of an appliance for practicing the game of golf comprising two reflectors attached to the golf club and each arranged to reflect in a predetermined direction towards the eye of a play-analyzing person a beam from an external source of light when the club is correctly oriented adjacent to the ball.

2. The combination with a golf club, of appliances for practicing the game of golf comprising two reflectors attached to the golf club and arranged to reflect by double reflection in a predetermined direction a single image of an external source of light when the club is correctly oriented adjacent to the ball.

3. The combination with a golf club, of appliances for practicing the game of golf comprising a double and a single reflector attached to the golf club and arranged to provide two images of a single source of light when correctly oriented adjacent to the ball.

4. The combination with a golf club, of appliances for practicing the game of golf comprising optical means to indicate the orientation of the club face about two co-ordinate axes at a predetermined point of the club's swing, said means comprising a plurality of reflectors attached to the club.

5. The combination with a golf club, of appliances for practicing the game of golf comprising optical means to indicate the orientation of the club face relatively to the desired trajectory substantially at the moment of impact with a ball, said means comprising a plurality of reflectors attached to the club, two of said reflectors being arranged to provide double reflection.

6. In combination, appliances for practicing the game of golf having means to indicate the orientation of the club face in relation to the desired trajectory of a ball comprising a plurality of reflectors attached to the club, and an external source of light consisting of a line-of-light lamp.

7. In combination, appliances for practicing the game of golf having means to indicate the orientation of the club face in relation to the desired trajectory of a ball comprising a plurality of reflectors attached to the club, and an external source of light constructed to have a relatively long and narrow luminous center.

8. The combination with a golf club, of means for practicing the game of golf comprising stationary luminous line forming means, and optical means carried by the club and containing a reflector movable thereby into correlation with said luminous line forming means to flash a line of light to indicate the orientation of the club face about two co-ordinate axes.
